(57) **CLAIM**

The ornamental design for a combined shaving cartridge with lubricating elements, as shown and described.

DESCRIPTION

FIG. 1 is perspective view of an ornamental design for a combined shaving cartridge and lubricating elements according to the present invention;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines illustrate portions of the combined shaving cartridge with lubricating elements and form no part of the claimed design.
